Primary Examiner — Lauren D McVey(74) *Attorney, Agent, or Firm* — Oblon, McClelland, Maier & Neustadt, L.L.P.(57) **CLAIM**

The ornamental design for a toner cartridge, as shown and described.

DESCRIPTION

FIG. 1 is a front, top, and right side perspective view of a toner cartridge in a first position;
 FIG. 2 is a rear, bottom, and left side perspective view thereof;

FIG. 3 is a rear, top, and left side perspective view thereof in a second position;

FIG. 4 is a front elevation view of FIG. 1;

FIG. 5 is a rear elevation view thereof;

FIG. 6 is a top plan view thereof;

FIG. 7 is a bottom plan view thereof;

FIG. 8 is a left side elevation view thereof; and,

FIG. 9 is a right side elevation view thereof.

The broken lines immediately adjacent to the shaded areas depict the bounds of the claimed design, while all other broken lines are directed to environment. The broken lines form no part of the claimed design.

1 Claim, 9 Drawing Sheets
